PROPORTIONAL MIXING MEANS

Harold Wright, De Kalb, and Charles E. Blackman, Waterman, Ill., assignors to De Kalb Agricultural Association, Inc., De Kalb, Ill., a corporation of Delaware

Application March 27, 1947, Serial No. 737,640

13 Claims. (Cl. 259—3)

1 This invention relates to an apparatus and a method for mixing materials. It has for one object to apply material to grain. This material may be a fungicide or any other material which it is desired to add to grain. An object is to provide means for mixing a dry ingredient with dry grain in measured proportions.

Another object is to provide a mechanism which will automatically mix and proportion grain and fungicide.

Other objects will appear from time to time throughout the specification and claims.

This invention is illustrated more or less diagrammatically in the accompanying drawings, wherein:

Figure 1 is a plan view of one form of the device;

Figure 2 is a side elevation with parts broken away and parts in section;

Figure 3 is a longitudinal vertical section taken on an enlarged scale at line 3—3 of Figure 1;

Figure 4 is a transverse section taken at line 4—4 of Figure 3 on a further enlarged scale; and

Figure 5 is a section taken at line 5—5 of Figure 2 on an enlarged scale.

Like parts are indicated by like characters throughout the specification and the drawings.

In the form shown, the invention comprises a rotary mixing member or assembly and two hoppers through which two types of material may be furnished for mixing. It also includes a conveyor for carrying material from one hopper and for introducing it into the rotary member or assembly.

The device may conveniently be supported on a foundation 1 and comprises a fixed outer drum or cylinder 2 which may be made in any manner. As shown, it is made of a single sheet given a cylindrical shape, and it is provided with members 3 which are secured together by bolts 4. At each end the drum or cylinder 2 is provided with supporting and closing plates. At the receiving end a plate 5 is secured to the drum 2 in any desired manner, and at the discharge end a plate 6 is similarly secured.

Mounted within the member 2 is a rotating cylinder 7 within which is a driving shaft 8. Spokes 9 connect the cylinder to the shaft. At its outer end the shaft 8 passes through a discharge or outlet housing 10 which is open at its

2 bottom, as at 11. The shaft is carried in bearings 12, 12 and carries a driving pulley 13. At the inlet end the cylinder 7 is carried on rollers 14, 14 which are supported on pins or shafts 15 fixed to the end wall 5. The cylinder 7 is thus carried at one end by the shaft 8 on the bearings 12 and at the other end on the rollers 14. The cylinder 7 may be driven in any manner. As shown it is driven by a belt 16 which is positioned about the pulley 13 and is also positioned about a smaller pulley 17 which is mounted on a shaft 18 carried in bearings 19, 19. Power is applied to the shaft 18 by the pulley 20. Within the cylinder 7 are fixed several helically arranged conveying and mixing vanes 21. They may be interrupted, as at 22, if desired.

Since the machine operates with dry ingredients, dust may be present or may be generated and, if desired, a vent pipe 23 may be in communication with the housing 10 and suction may be applied to the pipe 23 to establish an air current. The housing 2 is made dust-tight so that dust does not escape through it.

Generally the material which is to be treated is grain and a hopper 24 is provided. It is conveniently carried upon a support 25 which may be fixed to the end plate 5. The support, if desired, may be integral with the hopper 24. A slideable shutter or valve 26 is provided with an opening 27 and is positioned beneath the hopper 24 and may be provided with a handle portion 28 by means of which it may be moved back and forth to a position of adjustment suitable for the quantity of grain or other material which is passed through.

Beneath the hopper 24 is positioned a chute 29 which communicates with an opening 30 in the end wall 5. A ring-like member 31 may be positioned in the opening 30 to extend into the cylinder 7. If desired, the cylinder 7 is provided with an end wall 32 through which the member 31 extends.

The control valve 33 is mounted on a shaft 34 and lies under the opening 27 of the shutter or valve 26 and correspondingly under the open bottom of the hopper 24. A counterweight 35 is adjustably mounted on an arm 36 which is fixed on the shaft 34 by means of a collar 37. At its opposite end, particularly as shown in Figures 1 and 2, the shaft 34 carries a switch 38. This

switch may conveniently be a mercury switch. Whatever its construction, it is opened and closed by variations in its angular position as determined by movement of the shaft 34 under the influence of the grain falling upon the member 33. The switch 38 controls the operation of the feeding device which will be described below.

The means for feeding the second ingredient or material include a hopper 39 which is provided with a discharge opening 40 in its bottom. Material passing through the opening 40 is deposited upon the upper surface of a conveying member 41, which may be provided with a flexible cover 42. The member 41 is carried upon a plurality of springs 43 which are fixed to it, as at 44, and which at their opposite ends, as at 45, are fixed upon a base member 46. An electromagnet 47 is carried on a suitable base 48 and an armature 49 is fixed adjacent the magnet. As shown, it is carried upon one of the springs 43. A rheostat 50 is in circuit with the magnet 47, which is also in circuit with the switch 38. A switch 51 is in circuit with the magnet 47 and may be operated to turn the current off and on. A handle 52 is provided for the rheostat and by means of the handle the rheostat may be adjusted to vary the amount of current reaching the magnet. Automatic means are provided in the electric assembly to cause a pulsating current so that the magnet is constantly energized and de-energized. When it is energized it attracts the armature 49 and moves the member 41 to the right from the position shown in Figure 2. When the magnet is de-energized the springs 43 return the member 41 to the position shown in Figure 2. Thus the pulsating backward and forward movement of the member 41 is effective to carry material from the hopper 39 forwardly to the left, as shown in Figures 2 and 3, and to deposit the material inside of the cylinder 7 where it is mixed with the material entering from the hopper 24 through the chute 29. The quantity of material fed along the conveying member 41 is determined and may be varied by the setting of the rheostat 50.

Wires 53 connect the rheostat, the magnet, the switch 38 and the other parts of the electric assembly in circuit. If desired, a housing 54 may be provided for the switch 38. While it is ordinarily not necessary in a dry system, heating means such as the heating bar 55 shown in Figure 4 may be added, if desired.

The conveying member which includes the part 41 and the electrical assembly is not the object of the present invention, and such conveying assemblies are available on the market today.

Although we have shown an operative form of our invention, it will be recognized that many changes in the form, shape and arrangement of parts can be made without departing from the spirit of the invention, and our showing is therefore to be taken as, in a sense, diagrammatic.

The use and operation of this invention are as follows:

With the device assembled as shown, one material is furnished to the hopper 24 and another to the hopper 39. The cylinder 7 is rotated; the electric circuit is completed to the magnet 47, except for the position of the switch 38.

As the material falls through the hopper 24, it comes upon the member 33 and its weight tilts that member downwardly, thus moving the switch 38 to a position in which the circuit to the magnet 47 is completed. With the circuit to the magnet thus completed, the conveyor 41 is actu-

ated and material is conveyed from the hopper 39 to the cylinder 7. Thus so long as material is fed through the hopper 24 and the switch 38 is held in the position to complete the circuit, the two classes of material are fed in predetermined proportions to the cylinder 7.

Thus so long as material is fed through the hopper 24 and the switch 38 is held in the position to complete the circuit, the two classes of material are fed in predetermined proportions to the cylinder 7. In that cylinder they are moved and mixed from the right to the left toward the discharge end and are discharged into the housing 10. The heavier materials fall outwardly through the opening 11. Suction will generally be applied through the pipe 23 to establish the direction of air flow through the device and to prevent any back current or back flow through the opening at the inlet and where the grain and other material enter. The degree of suction may be controlled by an adjustable butterfly valve 23, if desired.

Should the flow of material through the hopper 24 stop, the counterweight 35 will carry the member 33 to the position of Figure 3, and in that position the switch 38 will be moved to the position in which it will break the circuit, and the magnet 47 will be de-energized and the conveyor 41 will be stopped. The rheostat 50 may be adjusted to control the operation of the conveyor 41 and thus to control the relative quantity of material from the hopper 39 which is mixed with the material from the hopper 24.

We claim:

1. In combination in a mixing and proportioning apparatus, a combined mixing and conveying member, and means for moving it, a main hopper, and means for conveying material from it into said member, a secondary hopper, and positive mechanical means for conveying material from it into said member, a gravity responsive member positioned in the path of said main hopper, and a member adapted to be moved by said gravity responsive means to stop the mechanical conveyor.
2. In combination in a mixing and proportioning apparatus, a combined mixing and conveying cylinder, and means for rotating it, a main hopper, and means for conveying material from it into said cylinder, a secondary hopper and positive mechanical means for conveying material from it into said cylinder, a gravity responsive member positioned in the path of said main hopper, and a member adapted to be moved by said gravity responsive means to stop the mechanical conveyor.
3. In combination in a mixing and proportioning apparatus, a combined a mixing and conveying cylinder, and means for rotating it, a main hopper, and means for conveying material from it into said cylinder, a secondary hopper, and electrical means for conveying material from it into said cylinder, electric circuit means for actuating said electrical means, a gravity responsive member positioned in the path of said main hopper, and a switch mounted to be moved by said gravity responsive means to break the circuit, to stop the electrical conveyor.
4. In combination for use in mixing and proportioning apparatus having a main hopper, and means for conveying material from it into a mixing and conveying member, a secondary hopper, and mechanical means for conveying material from it into said member, a gravity responsive member positioned in the path of said main

hopper, a combined mixing and conveying member, and means for moving it, a member adapted to be moved by said gravity responsive means to stop the mechanical conveyor, and an airtight housing about said apparatus, and means for exhausting dust and air therefrom.

5. In combination for use in a mixing and proportioning apparatus having a main hopper, and means for conveying material from it into said cylinder, a secondary hopper and mechanical means for conveying material from it into said cylinder, a gravity responsive member positioned in the path of said main hopper, a mixing and conveying cylinder, and means for rotating it, a member adapted to be moved by said gravity responsive means to stop the mechanical conveyor, and an airtight housing about said apparatus, and means for exhausting dust and air therefrom, said exhausting means establishing a current of air in the direction in which material is moved by said conveying cylinder.

6. In combination in a mixing and proportioning means, a mixing and conveying cylinder, and means for rotating it, members defining an inlet opening to said cylinder, and a discharge opening therefrom, a main and an auxiliary hopper, and means for conveying material from each of them to the interior of said cylinder, electrically operated conveying means from said auxiliary hopper, and a member positioned in the path of material flowing from said main hopper, a switch positioned to be actuated by said member, and means adapted, when the material passing through said first hopper falls below a predetermined minimum, to move said switch to break said circuit.

7. In combination in a mixing and proportioning means, a mixing and conveying cylinder, and means for rotating it, an airtight housing positioned about said cylinder, members defining an inlet opening to said cylinder, and a discharge opening therefrom, a main and an auxiliary hopper, and means for conveying material from each of them to the interior of said cylinder, electrically operated conveying means from said auxiliary hopper, and a member positioned in the path of material flowing from said main hopper, a switch positioned to be actuated by said member, said switch being in circuit with the means for operating said electrically operated conveyor, and means adapted, when the material passing through said first hopper falls below a predetermined minimum, to move said switch to break said circuit.

8. In combination in a mixing and proportioning device, a cylinder, means for rotating it, means for conveying a plurality of materials to said cylinder in predetermined proportions, one of said means including a hopper, and gravity directing means for directing material from said hopper to said cylinder, and a second hopper, and a positive conveying means for conveying material from said second hopper to said cylinder, and a valve member positioned in the path of material moving from said first hopper to said cylinder, and means effective in response to variation of flow of material through said first hopper to interrupt the operation of said positive conveyor when flow of material through said first hopper falls below a predetermined quantity.

9. In combination in a mixing and proportioning device, a conveying cylinder, means for rotating it, an airtight housing about said cylinder means for maintaining a current of air

through said housing in the direction of movement of material conveyed by said cylinder, means for conveying a plurality of materials to said cylinder, in predetermined proportions, one of said means including a hopper, and gravity directing means for directing material from said hopper to said cylinder, and a second hopper, and a positive conveying means for conveying material from said second hopper to said cylinder, and a valve member positioned in the path of material moving from said first hopper to said cylinder, and means effective in response to variation of flow of material through said first hopper to interrupt the operation of said positive conveyor when flow of material through said first hopper falls below a predetermined quantity.

10. In combination in a mixing and proportioning apparatus, a mixing and conveying member, and means for moving it, a main hopper, and means for conveying material from it into said member, a secondary hopper, and mechanical means for conveying material from it into said member, said mechanical means comprising a vibratory part and means for vibrating said part, a gravity responsive member positioned in the path of said main hopper, a member adapted to be moved by said gravity responsive means and thus to stop the mechanical conveyor, and an airtight housing about said apparatus, and means for exhausting dust therefrom, in the direction of movement of material passing through said apparatus.

11. In combination in a mixing and proportioning apparatus, a mixing and conveying member, and means for moving it, a main hopper, and means for conveying material from it into said member, a secondary hopper, and mechanical means for conveying material from it into said member, said mechanical means comprising a vibratory part and means for vibrating said part, a gravity responsive member positioned in the path of said main hopper, a member adapted to be moved by said gravity responsive means and thus to stop the mechanical conveyor, and an airtight housing about said apparatus, and means for exhausting dust therefrom at a variable speed, in the direction of movement of material passing through said apparatus.

12. In combination in a mixing and proportioning apparatus, a mixing and conveying member, and means for moving it, a main hopper, and means for conveying material from it into said member, a secondary hopper, and mechanical means for conveying material from it into said member, said mechanical means comprising a vibratory part and means for vibrating said part, a gravity responsive member positioned in the path of said main hopper, a member adapted to be moved by said gravity responsive means and thus to stop the mechanical conveyor, and an airtight housing about said apparatus, and means for exhausting dust therefrom in the direction of movement of material passing through said apparatus, said vibratory part positioned to withdraw material from said secondary hopper.

13. In combination in a mixing and proportioning apparatus, a mixing and conveying member, and means for moving it, a main hopper, and means for conveying material from it into said member, a secondary hopper, and mechanical means for conveying material from it into said member, said mechanical means comprising a vibratory part and means for vibrating

7
said part, a gravity-responsive member positioned in the path of said main hopper, a member adapted to be moved by said gravity-responsive means and thus to stop the mechanical conveyor, and an airtight housing about said apparatus, and means for exhausting dust therefrom at a variable speed in the direction of movement of material passing through said apparatus, said vibratory part positioned to withdraw material from said secondary hopper.

10 HAROLD WRIGHT.
CHARLES E. BLACKMAN.
